UNITED STATES PATENT OFFICE.

SAMUEL BARKER PRATT AND CLARA BARKER PRATT, OF BOSTON, MASSACHUSETTS.

THREAD-HOLDER FOR SPOOLS.

SPECIFICATION forming part of Letters Patent No. 397,999, dated February 19, 1889.

Application filed October 12, 1888. Serial No. 287,931. (No model.)

To all whom it may concern:

Be it known that we, SAMUEL BARKER PRATT and CLARA BARKER PRATT, both of Boston, in the county of Suffolk and State of 5 Massachusetts, have invented a new and useful Attachment for Spools of Thread, of which the following is a specification.

Spools of thread for domestic use are apt, especially when lying in a basket or work-box, to become more or less unwound, with the result that the thread from the different spools is liable to become tangled, and much trouble and loss of thread and time ensue therefrom. Our device is intended to obviate 10 this difficulty, to do away with any necessity for slitting or notching the spool, and to provide an end of the thread always ready for use, but at the same time to prevent the spool from becoming unwound any farther.

20 In the accompanying drawings, in which similar letters of reference indicate like parts, Figure 1 is an elevation of a spool of thread provided with our device. Fig. 2 is a horizontal section of the same. Fig. 3 is a similar section of the attachment removed. Fig. 4 is a plan of the main portion of the attachment laid flat, the elastic portion having been removed. Fig. 5 is a view of the elastic portion removed. Fig. 6 is a side view of a modification.

A represents a flat strip of thin pliable material—such as zylonite or some thin metal—broader at one end or portion and narrower at the opposite end or portion.

35 a is a hole situated near the end of the broad portion, of sufficient size to admit the end of the narrower portion.

b is a perforation centrally located in the strip, of a sufficient size to allow the passage of 40 the thread.

c is a hook or catch cut and formed up from the body of the strip.

A' is a hook formed by bending the end of the smaller portion of the strip back upon 45 itself.

A'' A''' are guiding-lips, produced by forming up the opposite edges of the broader portion of the strip at the points shown.

E represents an ordinary spool with the 50 thread e wound upon it in the usual manner.

The strip A is laid around the loaded spool in the manner shown—that is, with its narrower end projecting through the hole a, and the end of the thread projecting through the perforation b. An elastic band, D, catches over 55 the hook c and the hooked end A', extending from one to the other, as shown, between the lips A''. The object of this band is to force the strip to contract as the thread is unwound from the spool by pulling the narrow end 60 more and more through the perforation a in the broad end.

To remove a piece of thread, the spool is laid in the hand with the end of the thread extending between two upturned fingers 65 thereof. The thread is then pulled by the other hand, and the spool will rotate while the attachment remains stationary, and the thread be drawn through the perforation b until a sufficient quantity is unwound. The 70 spool may then be thrown into the work-basket without fear of more thread becoming unwound from it. In placing the spool in the hand preparatory to unwinding thread therefrom, it should be so laid therein that as the 75 thread is pulled the spool will rotate toward the palm of the hand. The attachment will readily follow the thread from end to end of the spool as it unwinds without any assistance.

80 It will be seen that in this attachment the strip is substantially flat, no groove or trough shape being necessary, as the elastic D is not obliged to extend entirely around the strip, the strip itself being provided with means for 85 securing the opposite ends of the elastic band on opposite sides of the outer free end of the strip.

The elastic band is prevented from coming in contact with the thread, thereby producing 90 too great friction thereupon, by means of the position of the hook c, which is sufficiently distant from the larger end to allow said strip to expand sufficiently, and still allow the hooked end A' to extend through the opening a, so that the portion of the strip between the opening a and the hook c is always interposed between the elastic band and the thread.

95 The elastic band is preferably, but not nec- 100

essarily made in the form of a figure 8, as shown in Fig. 5, in order that there may be two loops in said band, either of which may be caught over the hook *c*.

5 The modification in Fig. 6 shows the strip with the hooks *c* and *A'* and perforation *a* omitted, and the elastic band cemented at its ends to an end of the strip and to a portion near the center of the strip, as shown, so that the free end of the strip underlaps, (thereby keeping the elastic from contact with the thread,) and is held in position by means of loops *H*.

Having thus fully described our invention, 5 what we claim, and desire to secure by Letters Patent, is—

1. The strip *A*, provided with the perfora-

tion *a*, hook *c*, narrow hooked end *A'*, and perforation *b*, in combination with an elastic connection secured to said strip by means of 20 said hooks *c* and *A'*, substantially as and for the purpose described.

2. The strip *A*, provided with the perforation *a*, hook *c*, narrow hooked end *A'*, lips 25 *A''*, and perforation *b*, in combination with a double-looped elastic connection, *D*, secured to said strip by means of said hooks *c* and *A'*, substantially as and for the purpose set forth.
